UNITED STATES PATENT OFFICE.

ERNEST M. KARR AND JOSEPH A. BOUCHER, OF HUDSON, NEW YORK, ASSIGNEES TO GIFFORD-WOOD COMPANY, OF HUDSON, NEW YORK, A CORPORATION OF NEW YORK.

KNOB CUTTER.

Application filed May 1, 1926. Serial No. 106,140.

This invention relates to a knob cutter adapted to be used in connection with ice handling machinery. According to the method now in use in many modern ice manufacturing plants, the cans in which the ice is formed always remain in the brine and the ice is pulled upwardly out of the can by means of a hook or an eye which is frozen into the top of the cake. 5 With ice manufactured by this process there is a knob four or five inches in width and two inches or more in thickness formed on the bottom of the ice cake, which is caused by a flange or recess in the bottom of the can, this recess being used in filling the cans with water introduced through the bottom. 10

With ice manufactured by this process there is a knob four or five inches in width and two inches or more in thickness formed on the bottom of the ice cake, which is caused by a flange or recess in the bottom of the can, this recess being used in filling the cans with water introduced through the bottom. 15 The general object of the present invention is to provide means for removing this knob while the cakes of ice are being conveyed from the freezing tank to the storage room or delivery platform. According to the preferred method cakes of ice are lifted from the tanks by means of a crane which engages the hook or eye above referred to, and are then placed on end on a double conveyor, the knob being allowed to project downwardly between the two sides of the conveyor. 20

The present application is in part a continuation of an earlier application, Serial No. 30 44,010, filed by us, July 16, 1925.

The specific construction of the knob cutter embodying our invention, its mode of operation, and the advantages resulting therefrom will be more fully explained in the following detailed description which is to be read in connection with the accompanying drawings illustrating the same. 35

In the drawings:

Figure 1 is a plan view of the knob cutter and a portion of the conveyor and floor adjacent thereto, certain parts being broken away; 40

Figure 2 is a longitudinal section through the knob cutter showing also a portion of the conveyor and cakes of ice carried thereby; 45

Figure 3 is a vertical transverse section taken substantially on the line 3—3 of Figure 1;

Figure 4 is a front elevation of one of the severing devices enlarged, with a portion thereof shown in section; 50

Figure 5 is a longitudinal section through one of the cutter blocks;

Figure 6 is a view similar to Figure 3, but 55 showing a modified construction;

Figure 7 is an enlarged sectional view taken on the line 7—7 of Figure 6; and

Figure 8 is an elevation of the rotary cutter as viewed from the right of Figure 7. In carrying out the process above referred to, as shown in Figures 1 to 5 inclusive, the cakes of ice 10 are lifted from the cans and placed upon an endless conveyor which travels in a channel formed in the floor 11, the surface of the conveyor being slightly below the level of the floor. The illustrative conveyor comprises two spaced traveling members, each having a plurality of heavy slats 12 secured to angle irons 13 supported by a link belt 14 having rollers 15 which travel on tracks 16 secured to girders 17 located beneath the floor. The slats 12 during their travel are held in substantially horizontal position by guides 18 and 19. 60

As above stated, each cake of ice 10 as it is frozen has a knob 10^a left on the bottom and as the cake of ice is lifted from the can and placed upon the conveyor, this knob projects downwardly between the two series of slats 12 forming the supporting surface of the conveyor. By means of the invention herein described, this knob is entirely removed from the bottom face of the cake as the latter is being carried on the conveyor to the storage room or delivery platform. It will be clear 80 that while the removal of a knob from the bottom face of the cake is much to be preferred, it is within the scope of the present invention to remove a knob from an ice cake supported on other faces besides the one 85 from which the knob projects. 90

For supporting the knob severing devices, as shown in Figures 1 to 5 inclusive, in a position to effect the desired result, a series of bars 20 are secured in fixed relation to the tracks 16 by means of angle irons 21 or the like. These bars are arranged diagonally (Fig. 1) and traverse the space between the two sides of the conveyor and some distance below the surface thereof. 95

A base block 22 is secured to each bar 20 and above each base block is secured a holder 23. Each holder has a series of holes 24 extending longitudinally therethrough and inclined rearwardly and upwardly relative to the conveyor. The upper side of each hole 24 is rounded to form a seat for the rear portion of an ice pick 25, and the lower portion of the hole is flat and tapered rearwardly to receive a wedge 26 for securely fastening the pick in 100 105 110

the desired position. Each pick therefore is secured so that it extends rearwardly and upwardly into the path of the knob 10^a as the cake of ice is carried forwardly by the conveyor. Each pick terminates in a sharp tempered joint 27. Each successive base block 22 is somewhat thicker than the preceding base block so that the series of severing elements comprising the picks 25 are arranged in successively higher planes (Fig. 2). So that each successive group of severing element chips a small amount of ice from the knob until the latter is completely removed without injury to the ice cake.

15 The foremost base block 28 is preferably formed with a flat inclined upper surface and a flat cutting blade 29 is secured thereto having a tempered beveled edge which is disposed substantially in the same plane as the upper surfaces of the slats 12 so that the bottom face of the ice cake is finally left perfectly plane. It will be noted that the holders in which the picks are secured are in a diagonal position so that no two picks enter 25 the ice at the same time. This feature, of course, minimizes the possibility of the picks retarding the movement of the ice as it is carried along by the conveyor.

In the form shown in Figures 6, 7 and 8, 30 conveyor members 30 are supported by rollers 31, which are adapted to ride on tracks formed by angle bars 32, supported by a suitable steel framework 33 beneath the floor 11. Bearings 34 are secured to the undersides of 35 certain of the angle bars 32, and rotatably support a cutter shaft 35 which is driven from a suitable motor 36 supported on a platform 37 beneath the floor. A cutter head 38 is secured to the shaft 35, and is formed with 40 flat faces 39 forming seats for cutter blades 40. These blades are secured by bolts 41, which may be inserted in longitudinal slots 42 in the cutter head, the blades being provided with slots 43 for receiving the bolts. 45 The cutter head 38 is adapted to be rotated rapidly by the motor 36, so that as the block of ice is carried along by the conveyor elements 30 with the knob 10^a projecting downwardly into the path of the cutting blades 40, the latter will shave off successive slices from 50 the knob until the latter is completely removed, leaving the bottom face of the ice cake perfectly plane.

The severing devices 25 and 29 or 40, as 55 the case may be, are so arranged that the knobs are removed by successive cuts during the normal conveyance of the ice from the tank to the storage room or point of delivery, so that no extra handling is necessary. The 60 block of ice remains in the same relative position as it occupies when in the can, with the knob projecting from the bottom end until it is severed therefrom.

Obviously the present invention is not restricted to the particular embodiment thereof

herein shown and described. Moreover, it is not indispensable that all the features of the invention be used conjointly, since they may be employed advantageously in various combinations and sub-combinations.

70

What is claimed is:

1. A device for removing a knob from the bottom face of a cake of ice, comprising two spaced conveyer members having slats on which the cake is supported with the knob projecting downwardly between said conveyer members, a roller mounted on the underside of each slat centrally thereof, parallel tracks on which the rollers ride, a guide underneath each side of each conveyer member for supporting and guiding all of said slats in a common plane during their forward travel, and severing devices between the conveyer members and in the path of the knob as the cake of ice is carried forwardly, said severing devices being operable to remove the knob during the transit of the cake, leaving a plane bottom surface.

75

2. A device for removing a knob from the lower face of a cake of ice, comprising two spaced traveling members adapted to support the cake with the knob projecting downwardly between said two members, and a succession of severing devices located in successively higher planes in the path of said knob and operable to trim off successive portions of said knob during transit of the cake thereover, the last of said severing devices being in the same plane as the upper surfaces of said traveling members, so that the cake has a plane bottom surface when it leaves the same.

80

3. A device for removing a knob from the lower face of a cake of ice, comprising two spaced traveling members adapted to support the cake with the knob projecting downwardly between said two members, and a plurality of stationary severing devices located one behind the other between said two members, each succeeding severing device being in a higher plane than the one preceding, the last severing device being in substantially the same plane as the upper surfaces of the travelling members, so that the cake as it leaves the same has a plane bottom surface.

85

4. A device for removing a knob from the lower face of a cake of ice, comprising two spaced traveling members adapted to support the cake with the knob projecting downwardly between said two members, a succession of severing devices each comprising a series of picks inclined upwardly into the path of the knob, each succeeding series being higher than the preceding, and a final severing device comprising a blade supported with its edge in the same plane as the upper surfaces of said traveling members.

90

5. A device for removing a knob from the lower face of a cake of ice, comprising two spaced traveling members adapted to support

130

the cake with the knob projecting downwardly between said two members, a succession of severing devices each comprising a diagonally disposed block with a plurality of ice picks 5 supported thereby and inclined upwardly into the path of said knob so that no two picks will be engaged by the ice at the same time, each succeeding severing device being higher than the preceding, and a final severing device 10 comprising a blade supported with its edge in the same plane as the upper surfaces of said traveling members.

6. An ice cutting device for acting on the lower face of an ice block comprising, in combination, a series of stationary blocks arranged one behind the other, each successive block having its upper face higher than the preceding, a series of ice picks supported by each of said blocks, the points of said picks 20 being higher than the upper surfaces of the respective blocks, a final block, and a blade secured to said final block and terminating in an edge which is slightly higher than the points of the last series of picks; and means 25 for moving blocks of ice over said cutting device.

7. An ice cutting device for acting on the lower face of an ice block comprising, in combination, a series of stationary blocks arranged one behind the other, a holder secured to the upper face of each block, a series of picks secured in each holder and extending forwardly and upwardly, each holder being disposed diagonally whereby the picks secured thereto are arranged one in advance of the other, and each successive block having its upper face higher than the preceding so that the picks supported thereby project higher than the picks of the preceding block; 30 and means for moving blocks of ice over said cutting device.

8. An ice cutting device for acting on the

lower face of an ice block comprising, in combination, a series of stationary blocks arranged one behind the other, a holder supported by each block and having a series of picks extending forwardly and upwardly therefrom, each holder being disposed diagonally whereby the picks carried thereby are arranged one in advance of the other, each successive block having its upper face higher than the preceding so that the picks supported thereby project higher than the picks supported by the preceding block, a final block in rear of the aforementioned blocks, and a 45 blade secured to said final block and terminating in an edge which is slightly higher than the points of the last series of picks; and means for moving blocks of ice over said cutting device.

9. In a device for removing a knob from the lower face of a cake of ice, a conveyor adapted to support the cake with the knob projecting downwardly, and a succession of severing devices located in successively higher planes in the path of said knob and operable to trim off successive portions of said knob during transit of the cake so that the cake has a plane bottom surface when it leaves the conveyor.

10. A device for removing the knob formed on a cake of artificial ice during its manufacture, comprising means for supporting and conveying the cake with the knob projecting downwardly therefrom, and means below the 65 surface of the conveyor for severing successive portions of the knob, while the cake is so conveyed, until all of the knob is removed, leaving the bottom face of said cake plane.

In testimony that we claim the foregoing 70 as our own, we have hereto affixed our signatures.

ERNEST M. KARR.
JOSEPH A. BOUCHER.
